BANDAGE BINDER CLIP

Ernest Freiberg, Brooklyn, N. Y.

Application August 26, 1937, Serial No. 160,941

3 Claims. (Cl. 24—85)

My invention relates to a bandage binder or clip, and it is the principal object of my invention to provide a clip or clasp adapted to be secured to each end of an elastic strip used to read-
 5 ily secure gauze and other bandages over wounds, said clips having each a frame, the bars of which are of substantially semi-circular cross-section to provide a groove into which the pointed warts or the sharp ridge of a metal plate formed with one
 10 of the frame bars of the clasp are engaging and clamping the material of the elastic strip when said metal plate is bent upon the strip to hold the ends of the strip securely and non-displaceably on the clip.

15 Another object of my invention is the provision of a binder or clip for bandages which is of a simple and inexpensive construction, yet durable and highly efficient in use.

Bandage fasteners formed from a flat strip of metal provided with hooks and having a clamping leaf projecting from the frame of the metal strip, and overlying the prongs projecting at right angles from the metal strip are known, however, these fasteners have the disadvantage, that they are comparatively complicated and therefore expensive and inconvenient to use while lacking in firmness so as to cause the bandages to slip and thus contribute to irritations of the wounds or the like.

30 It is the object of my invention to provide a bandage clip avoiding these disadvantages by providing the clamping plate or leaf with a plurality of pointed warts or a sharpened ridge intermediate the ends or sides thereof which, when
 35 said plate is bent down upon the ends of the elastic strip, will firmly press the material of the strip into the groove of the frame bar of the clasp by a simple and convenient operation and will hold the elastic strip firmly to the clasp or vice
 40 versa.

These and other objects and advantages of my invention will become more fully known as the description thereof proceeds and will then be specifically defined in the appended claims.

45 In the accompanying drawing forming a material part of this disclosure:

Fig. 1 illustrates the application of the bandage binder constructed according to my invention to a wound dressing upon the wrist.

50 Fig. 2 is a front elevation of one clasp member of the binder on a somewhat enlarged scale.

Fig. 3 is a section on line 3—3 of Figure 2.

Fig. 4 is a rear view of one of the clasp members also on a somewhat enlarged scale.

55 Fig. 5 is a rear elevation of a clasp member of

a modified construction, also somewhat enlarged.

Fig. 6 is a section on line 6—6 of Figure 5.

As illustrated, the clasp members 10 and 11 are attached to the elastic strip 12 to hold the ends of a bandage 13 in their overlapping position.

Each of the clasp members comprises a substantially rectangular frame 14, the bars of which are substantially semi-circular in cross-section, as indicated at 15, to form grooves 16. A plate 10 or leaf 17 is made integrally with the lower frame bar and can be bent upon the rear face of the lower frame bar. The outer face of the leaf plate carries a plurality of sharp or pointed prongs or teats 18 adapted to engage the material of the elastic strip 12 and press the same into the groove 16 of the respective clasp member to thus securely hold the same to the end of the strip. Prongs 19, 20 are formed with the edges of the frame bar oppositely disposed to the 20 bar having the plate formed therewith and are rearwardly bent so as to readily engage the material of the bandage.

In the modified form of my invention illustrated in Figures 5 and 6, the plate or leaf 21 is 25 provided at its inner face with a longitudinally extending ridge 22 adapted to be pressed into the material of the strip 23 and to press the same into the groove 24 of the clasp member 25 also having prongs 26 formed at its rear bar opposite 30 to the leaf 21 and adapted to engage the material of the bandage 13.

In use the binder will be securely fastened by means of the clasp or clip members, particularly their prongs to the bandage and when then the 35 leaves or plates of the clip members are bent upon the ends of the elastic strip, their teats or ridges will securely and firmly press the material of the strip into the grooves of the clasp members so that these ends cannot become loose 40 or displaced while a simple rearward bending of the leaves or plates will suffice to release the strip for the removal of the bandage.

Thus, the simple operation of the leaf or plate of each clasp member will firmly attach the ends 45 of an elastic strip thereto or vice versa, while the prongs embedded into the bandage will hold the same with its overlapping ends securely to a wound without danger of displacement.

It will be understood, that I have described and 50 shown the preferred forms of my invention only as one example of the many possible ways to practically construct the same, and that I may make such changes in its general arrangement and in the construction of the minor details 55

thereof, as come within the scope of the appended claims without departure from the spirit of my invention and the principles involved.

Having thus described my invention, what I claim as new, and desire to secure by Letters Patent is:

1. A bandage binder clip comprising a frame, the bars of which are of semi-circular cross-section to form a groove, and a plate bendably connected to a bar of said frame, a plurality of teats formed with said plate adapted to press the material of an elastic band into the groove of said frame when said plate is bent upon said band, and a means to secure said binder to a bandage.
- 10 2. A bandage binder clip comprising a substantially rectangular frame the bars of which have semi-circular cross-section to form grooves, a leaf or plate connected to one of the side bars

of said frame adapted to be bent out of the plane of said frame, a longitudinally extending ridge formed with said plate adapted to press the material of an elastic band into the groove of said frame bar when said plate is bent upon said band, and a means to secure said binder to a bandage.

15 3. In a bandage binder clip as described, a substantially rectangular frame made from material substantially semi-circular in cross-section so as to form a marginal groove, a plate adapted to be bent at the point of its connection with the frame out of the plane of same and provided with means co-operating with the groove to clamp an elastic band to said frame, and a pair of prongs formed with said frame normally bent down upon the same at the outer corners for securing said clip to a bandage.

ERNEST FREIBERG.
